GAS IGNITING AND BURNING DEVICE

George Herbster, Cleveland, Ohio, assignor to
The Cleveland Cooperative Stove Company,
Cleveland, Ohio, a corporation of Ohio

Application January 30, 1933, Serial No. 654,162

10 Claims. (Cl. 158—115)

This invention relates to an apparatus for effecting more efficient firing relation between a service burner and pilot burner.

One of the principal objects of the present invention is to insure substantially instantaneous ignition of the service burner by the pilot burner under the most adverse conditions.

Another object is to provide an ignition burner in firing relation to both the pilot and service burners, which ignition burner will operate substantially instantaneously with the introduction of fuel thereto.

A more specific object resides in the provision of a new and improved service burner having in combination therewith an ignition burner for the purpose described.

Another specific object is to provide a new and improved valve for supplying fuel through different nozzles directly from the feed line both to the service burner and to the ignition burner.

Still another object is to provide a valve for this purpose adapted, upon turning in a given direction, first to introduce fuel to the ignition burner, and upon subsequent turning in the same direction, to maintain the flow of fuel to the ignition burner and introduce fuel to the service burner, whereby the ignition burner may be supplied with fuel before and concurrently with the supply to the service burner, and adapted, upon operation of the valve in the opposite direction to discommunicate the gas supply to the service burner, and subsequent thereto to discommunicate the ignition burner.

Other objects are to provide a valve of this character with a new and improved clutch means between the operating stem and plug for rendering the valve more safe from interference by children, and to provide a means for positively locking the valve in a position to supply gas to the service burner so as to maintain a simmering flame thereon.

Other objects and advantages will become apparent from the following specification wherein reference is made to the drawings.

45 In the drawings, Fig. 1 is a plan view of a service and ignition burner and control valve embodying the principles of the present invention.

Fig. 2 is a side elevation of the burners and valve shown in Fig. 1, part of the burners being 50 shown in section for clearness in illustration.

Fig. 3 is an enlarged sectional view illustrating the relation between the ignition burner and a pilot light, part being taken on a plane indicated by the line 3—3 of Fig. 1.

55 Fig. 4 is an enlarged sectional view of the con-

trol valve and is taken on a plane indicated by the line 4—4 of Fig. 2.

Fig. 5 is a sectional view of the valve taken on a plane indicated by the line 5—5 of Fig. 4.

Figs. 6 and 7 are sectional views of the valve 60 taken on planes indicated by the lines 6—6 and 7—7 of Fig. 5.

Figs. 8, 9, 10 and 11 are sectional views of the valve taken on a plane indicated by the line 8—8 of Fig. 5, showing different operating positions 65 of the valve plug; Fig. 8 showing the position of the plug when both burners are cut off; Fig. 9 the ignition burner on and the service burner off; Fig. 10 the ignition burner on and the service burner at simmering position, and Fig. 11 both 70 burners fully on.

Fig. 12 is a fragmentary sectional view showing a modified form of clutch and simmering stop.

Fig. 13 is a fragmentary sectional view of a 75 service burner and a modified type of ignition burner.

In my copending application, Ser. No. 654,161 filed January 30, 1933, the advantages of a plurality of service burners ignited from a common 80 pilot through the medium of firing tubes have been fully described. In the said application, it also has been pointed out that it is desirable to provide an ignition burner for insuring firing relation between the pilot and service burners, the 85 ignition burner and service burner being controlled by the same valve and arranged so that upon turning the valve from the closed position in one direction, gas is first introduced to the ignition burner and subsequently to the service 90 burner, the supply to the ignition burner being maintained during the operation of the service burner and being cut off after the supply to the service burner has been cut off. Further, in my copending application I described a particular 95 discharge nozzle for the ignition burner to insure lighting thereof and of the service burner consequent upon a flashing through the firing tube.

Experience has proven that the device therein 100 described operates in a very few seconds. However, it is desirable that the same operate almost instantaneously, or about as promptly as the service burner would be ignited were a lighted match held at the discharge vents.

The present invention provides a means for effecting a more prompt introduction of gas to the ignition burner so that a flame is established substantially coincident with the discharge of gas from the service burner.

105

110

A suitable service and ignition burner combination for accomplishing this result is illustrated in Figs. 1 to 3 inclusive, the service and ignition burner being formed integral for compactness and for adaptability to existing types of gas ranges. Referring to the figures, a front right-hand service burner for a domestic cooking range is illustrated, the burner comprising the usual hollow burner head 1 provided with a plurality of radial arms 2, each having the usual discharge vents 3. Communicating interiorly with the head 1 is a mixing chamber 4 having at its inlet end a mixing bell 5 into which gas is discharged for supplying the burner.

The ignition burner comprises a hollow burner head 10 having a mixing chamber 11, the chamber 11 having a mixing bell 12 at the inlet end for reception of gas and air supplied to the ignition burner. The burner head 10 may be formed, as described, integral with the service burner, preferably as a continuation of one of the arms 2 thereof. The burner 10 and chamber 11, however, are discommunicated from the interior of the head 1 and chamber 4 except, however, in some cases, a by-pass duct 13, for purposes later to be described, is provided. The ignition burner head 10 is provided with a large vent 15 adapted to receive the neck of a discharge nozzle, later to be described, and better illustrated in Fig. 3, the vent 15 preferably being spaced a distance from the end of the outermost vent 3 of the arm of the burner with which associated. Intermediate the vent 15 and the particular vent 3 described, are a plurality of vents 16, these vents being arranged to be ignited consequent upon flashing of gas from the firing tube and ignition of the jets issuing from the discharge nozzle provided in the vent 15.

As more fully described in my copending application, this discharge nozzle, designated at 20, is provided with an upright duct 21 which communicates with the interior of the ignition head 10, and a transverse duct 22, communicating with the duct 21 and discharging directly into the firing tube 23. The firing tube in turn discharges at the opposite end near the pilot burner 24. A second transverse duct 25 which likewise communicates with the duct 21 and preferably discharges at 90° to the duct 22 is provided in the nozzle 20. Mounted on the nozzle 20 is a movable head 26 provided with a baffle 27 which depends from the head in spaced relation to and in front of the discharge opening of the duct 25. The head is preferably mounted as illustrated, by means of a screw 28 so that it can be positioned to deflect gas discharged from the duct 25, both toward the firing tube and discharge point of the duct 22 and toward the passages 16 of the ignition burner, so as to insure a flame from the end of the firing tube to the ignition vents 16.

For introducing gas into the bells 5 and 12 and thus to the respective ignition and service burners, a gas cock or valve, the body of which is indicated at 30, is provided. As more fully described hereinafter, this valve is provided with ducts directly communicating with a main gas supply pipe and with nozzles 31 and 32 respectively, the nozzle 31 discharging into the bell 5 and the nozzle 32 discharging into the bell 12 leading to the ignition burner. Thus the amount of gas supply to each of said burners may be independently regulated.

Assuming that the gas cock has been set in the "off" position, as it is turned in the direction for

communicating the service burner with the gas supply, gas is first introduced from such supply to the nozzle 32 and consequently to the ignition burner. Upon additional turning in the same direction, gas is supplied to the service burner through the nozzle 31, the supply to the ignition burner continuing, and, upon additional turning in the same direction, the ignition burner continues operation and the flow to the service burner is increased. Since the outlet vents of the ignition burner are relatively small, if a large amount of gas is supplied through the nozzle 32, it cannot readily pass to the vents 15 and 16 due to the air and back pressure within the mixing passage 11. By increasing the flow of gas to the nozzle 32, this air can be rapidly expelled but too large a supply of gas through the ignition burner would thereafter exist during continuous burning. Furthermore, there would be a tendency for the gas to fill the tube 11 more quickly than the air was expelled and consequently, part of it would back out of the open end of the bell 12.

Again, a small flow of gas introduced into the comparatively large head 1 requires some few seconds to fill the head and issue from the vents 3. Consequently, it is desirable that a large flow be introduced to the service burner when first "cut on" and, in fact, the operator usually opens the valve to full open position when first starting the burner.

Since the service burner is provided with a large number of outlets 3, this large volume of gas from the nozzle 31 readily passes into the service burner, and substantially no back pressure is built up. Therefore, upon opening the valve, the flow of gas through the nozzle 32 to the ignition burner in a sufficient quantity for maintaining the proper continuous small flame thereon is not large enough to reach the ignition burner promptly, due to the back pressure, while that from the nozzle 31 more promptly passes to the service burner so that gas issues from the service burner at an interval before it issues from the ignition burner. To overcome this objection, and to insure a prompt flow of gas to the ignition burner, the by-pass passage 13, above mentioned, is provided. This passage 13 communicates the interior of the ignition head with the interior of the service burner head, and is preferably arranged well below the vents 15 and 16 of the ignition head and in a position out of the direct path of movement of the main stream of gas. This opening is sufficiently large so that air in the tube 11 may readily pass into the service burner, wherefrom it will be exhausted and relieve any back pressure in the chamber 11, and consequently, will permit a rapid initial flow of gas from the nozzle 32 into the head of the igniting burner. When the gas in the tube 11 reaches the igniting burner, substantially all the air has been expelled, a small amount only remaining in the head. Since the gas is lighter than air, any remaining air will be easily displaced downwardly through the passage 13, permitting the gas to flow readily to the passages 15 and 16 without objectionable back pressure.

By virtue of this by-pass, a larger amount of gas may be supplied through the nozzle 32 for accelerating the initial flow to the ignition burner and any excess gas will pass through the by-pass 13 and into the adjacent arm 2 of the service burner and thus be discharged through the ducts 3 nearest to the ignition burner. As a result, the flame from the firing tube or the nozzle 20 and 150

issue of gas from the vents 16 will occur substantially at the same time that gas first issuing from adjacent vents 3 of that particular burner arm, so that firing relation is assured. These jets 16 provide sufficient gas to form a continuous path between the discharge nozzle 20 and the burner arm so that the flame may be formed from the nozzle to the vents 3. Obviously, when a large supply of gas is provided to both the ignition and service burners, this supply can substantially equalize through the by-pass 13 so that the two act as a single large burner with a few additional vents. During the period of high flame on the service burner, a venturi effect is produced tending to draw gas from within the ignition burner into the service burner through the by-pass.

In order to effect the proper flow of gas to the respective nozzles 31 and 32, a valve, such as illustrated in Figs. 4 to 11 inclusive may be provided.

This valve comprises a body 30 having a suitable plug receiving bore 34 in which is mounted a rotatable plug 35. The body is provided with a plurality of ducts, one of which, designated at 36, communicates with a gas supply and with the bore 34, the others being discharge ducts 37 and 38 which communicate with the bore 34 and respectively with the discharge nozzles 31 and 32. The plug 35 is provided with a radial duct 39, positioned axially of the plug to register with the duct 36 in one rotated position of the plug. The plug is also provided with an axially extending duct 40 communicating with the duct 39 and with ducts 41 and 42 respectively, the ducts 41 and 42 being adapted for registry with the respective ducts 37 and 38 in various rotated positions of the plug 35. The ducts 41 and 42 may be coaxial, the axis thereof being offset transversely of the plug from the plug axis, or, if desired, one of said passages only may be offset, the axis of the other intersecting and being normal to the plug axis. In event the valve is used with a left-hand burner in which the mixing chambers leading to the respective burners are positioned oppositely from the burner illustrated, the passages

would be offset in the opposite direction for effecting the same operating relation when the valve is turned in the same direction. The reason for offsetting the passages 41 and 42 in the manner described is best illustrated by reference to Figs. 8 to 11 inclusive. For example, referring to Fig. 8, the plug is shown in the cutoff position, wherein the ducts 41 and 42 respectively are offset from the ducts 37 and 38, the duct 39 being offset from the duct 36. If the valve plug is rotated in a counter-clockwise direction, it first assumes a position illustrated in Fig. 9, wherein the duct 39 is communicated with the duct 36 to supply gas into the axial duct 40, the duct 40 being in communication through the duct 42, with the duct 38 leading to the ignition burner nozzle 32 and the duct 41 leading from the duct 40 being disconnected from the duct 37 leading to the service burner. Consequently, gas will first be supplied only to the ignition burner. Upon continued rotation to the position illustrated in Fig. 10, a slightly increased flow is provided through the duct 42 to the ignition burner and a sufficient flow introduced through the duct 41 to the service burner to maintain a flame thereon of sufficient intensity for simmering. Additional rotation of the valve in the same direction effects a full communication through the duct 41 to the service burner and through the duct 42 to the ignition burner. Since a much smaller amount of gas is discharged through the nozzle 32 due to the set-

ting thereof, the registry of a small amount of the duct 42 with the duct 38 will supply as much gas to the ignition burner nozzle 32 as will be discharged thereby. Consequently, a full flow is maintained from the instant that the duct 42 is slightly in register and during the entire period of operation of the service burner, regardless of the degree of flow to the latter.

Obviously, the plug passages and plate 60, later to be described, can be reversed, if circumstances so require, so that the same order of operation is obtained by turning the valve clockwise.

In order to rotate the plug and yet to render it comparatively safe from operation by children or uninstructed persons who might inadvertently turn on the gas supply, there is provided a clutch device for effecting a connection between the valve stem and the plug, which device normally is disconnected and which for connection requires that the stem be moved axially inwardly and thence rotated while held in this inward position.

Referring to Figs. 4 to 7, an operating stem 45 is mounted for independent rotary and axial movement in a suitable sleeve 46 which may be formed in the end closure cap 47 secured to the body 30. The inner end of the stem protrudes inwardly of the valve body and into a suitable coaxial recess or bore 48 in the plug 35. The inner end of the stem is provided with a bore 49 coaxial with the bore 48. In the walls of the stem bore 49 are longitudinally extending slots 50 which may be positioned diametrically opposite to each other, and which open at the inner end of the stem. Mounted in the slot 50 is a dental clutch member 51 which may be in the form of an H-shaped bar extending diametrically of the stem 45 and protruding laterally beyond the limits of the stem, the clutch member being positioned against the end wall of the slots 50 and secured in place by a suitable pin as illustrated in Figs. 5 and 6. The ends of the clutch member terminate each in a pair of oppositely disposed clutch teeth, such as indicated at 52 and 53, preferably extending longitudinally of the stem. A spring 54 is mounted in the stem bore, one end of the spring abutting the end wall of the bore 48 in the plug and the opposite end abutting the dental clutch member 51 so as to urge it and the stem away from the plug. The plug 35 is provided with suitable means adapted for engagement with the inwardly disposed clutch teeth 52 of the clutch member so as to effect rotation of the plug consequent upon rotation of the clutch. In the form illustrated, such means may comprise recesses, as indicated at 55, adapted for registry with and to receive snugly the clutch teeth 52 when the same are aligned therewith and moved axially toward the plug.

Referring to Fig. 6, the backing plate 47 is provided with recesses 57 positioned for registry with the outwardly extending clutch teeth 53 and adapted to receive these teeth. The recesses 55 and 57 are positioned relative to each other and to the fuel ducts in the plug so that when the plug is in the cut-off position, the recesses 55 and 57 are in axial alignment. Consequently, due to the action of the spring 54, the clutch member is moved axially away from the plug to dispose the teeth 53 within the recesses 57, thus allowing the clutch member 51 to move away from the plug a sufficient distance so that the teeth 52 are disengaged from the recesses 55. In this position, the stem is locked and cannot be rotated except upon sufficient inward movement of the stem to 150

disengage the teeth 53 from the recesses 57; this amount of movement being likewise sufficient to engage the teeth 52 with the recesses 55 of the plug. Obviously, when the handle is moved axially inwardly to effect this disengagement and then rotated a slight amount, the outer ends of the teeth 53 may bear against the plate 47, thus holding the teeth 52 in engagement with the recesses in the plug and permitting rotation of the plug and handle together without further inward movement or holding of the stem inwardly by the operator.

To stop rotation of the stem and plug in off position when moving from the on position, so that clutch teeth 53 are aligned with and may enter the passages 57, stops or nibs 58, better illustrated in Fig. 6, may be provided on the plate 47, these nibs being conveniently formed from the metal stamped out to form the passages 57.

In some instances, it may be desirable to provide a positive stop and locking means positioned so that after the valve plug has been rotated to fully opened position it may be stopped upon return to maintain the flame on the service burner at a suitable height for simmering. For accomplishing this purpose, a stop plate 60 may be provided, this plate being secured by a suitable screw 61 to the body 30 of the valve and being provided with a slot 62 to permit rotation of the same relative to the valve body for effecting proper adjustment relative to the clutch for the particular size of simmering flame required. This plate is provided with recesses 63 alignable with the recesses 57 and elongated slots 64. The metal intermediate the recesses 63 and slots 64 provides stops 65 which lie in the path of the teeth 53 when the teeth 53 extend through the slots 64 with their ends bearing against the plate 47. The duplicate recess, slot, and stop are placed for simultaneous engagement with the respective teeth 53 of the clutch member.

Referring to Fig. 7, assuming the teeth 53 lie within the passages 57; while so received they extend through the recesses 63 in the plate 60. The stem must be moved axially inwardly to disengage the teeth 53 from the passages 57 and when in this position, engage the recesses 55 in the plug so that upon turning the stem, the plug is turned. This inward movement should be sufficient to dispose the teeth 53 inwardly from the recesses 63 and stops 65 so that the plug may be fully opened. As soon as the clutch teeth have passed the stops 65, if the stem is then released, the teeth 53 will be urged into contact with the plate 47 while still in engagement with the plug recesses 55, and thus held engaged. When so held, if the stem is rotated in the opposite direction, i. e., toward the cutoff position, the teeth 53 will engage the stops 65, the stops 65 being so positioned to effect this engagement when the plug has been rotated to cause a simmering flame on the service burner. To completely close the valve, it is necessary to again shove the stem inwardly to carry the teeth 53 inwardly from the stops 65, and turn the same slightly toward cut-off position, after which the stem may be released and the teeth 53 will engage and slide along the plate 47 until the teeth again pass into alignment with the openings 57 and snap into place therein to lock the valve in the closed position. For clearness in illustration, radial lines, indicated at P^8 , P^9 , P^{10} and P^{11} have been shown on Fig. 7, the lines showing the rotated position of the clutch for different operating positions of the plug, the clutch being in position P^8 when the plug is in

the off position, illustrated in Fig. 8; in position P^9 when the plug is rotated to turn on the igniting burner only, as illustrated in Fig. 9; in position P^{10} when the plug is in position to cut on the flow of gas to both the service and igniting burners, the flow to the latter being sufficient to permit only a simmering flame, as illustrated in Fig. 10, and in position P^{11} when the plug is in the open position for full operation of both burners, as illustrated in Fig. 11.

In some instances, it is desirable to provide a means for stopping rotation of the plug in a position to maintain the simmering condition of the service burner, as described above, which means will not only positively stop and hold the plug at this position but, if sufficient torque were exerted on the stem to damage the plug or clutch, would disengage and permit rotation of the plug to closed position. Such an arrangement will assure the operator that the simmering position is reached more effectively than the usual snap action which permits easy additional turning, and at the same time, will prevent damage to the valve by undue twisting of the stem by an un instructed operator. Such a means is illustrated in a modification shown in Fig. 12, wherein the parts corresponding to the parts above described are indicated by prime numbers corresponding to the numbers above used. Thus the clutch teeth 53' may be provided on the edge leading in the direction of rotation for cutting off the gas with a comparatively steep cam surface 70, which, upon engagement with the bridge or lug 60' will arrest rotation of the clutch, but which, when an extremely heavy torque is exerted on the stem, will lift up over the lug 60 and pass to the position in which the plug would cut off completely the supply of gas to both burners.

As above explained, the ignition burner insures lighting of the service burner promptly. In order to more effectively utilize the fuel discharged therefrom, the ignition burner may be in the form illustrated in Fig. 13, wherein parts corresponding to the parts illustrated in Figs. 1 to 3 are designated by corresponding primed numerals. In this embodiment, the part of the top wall of the ignition burner in which the nozzle 20' is mounted is stepped down below the level of the remainder of its top wall and the top wall of the burner arm 2'. In this lower portion of the top wall of the ignition burner and in the upper portion are vents 16' which are preferably smaller than the vents 3' of the service burner so as to form elongated flames. In the upwardly extending wall portion 80, joining the two top wall portions of the ignition burner are vents 81 which discharge over the lower top wall portion and toward the firing tube 23'. The offset between the top wall portions is such as to bring the firing tube in position to discharge over the upper surface of the burner arm 2'. Due to the vents 80, a body of fuel is maintained from within the discharge end of the firing tube over the surface of the ignition burner and burner arms 2', thus insuring a flash between the tube and burners. For a reason now unknown but apparently because of swirling of the gas entering the head of the ignition burner, the discharge of gas therefrom is at a higher pressure or rate of flow than from the service burner, even when the by-pass 13' is provided and operating, but too great an excess of fuel to the ignition burner will be relieved through the by-pass and pass to the vents 3'.

It is apparent from the foregoing description

that the invention provides an efficient means for increasing the rapidity of the ignition of the service burner from the pilot burner and for effectively controlling the operation of the respective burners from a single operating valve or gas cock.

Having thus described my invention, I claim:

1. In a gas burning device, a pilot burner, a service burner, an ignition burner in firing relation to the pilot burner and having a discharge vent in igniting relation to the service burner, individual mixing tubes leading one to the ignition burner and one to the service burner, separate means for discharging gas into the respective mixing tubes, and means for passing excess air and gas from the ignition burner into the service burner.

2. In a gas burning device, a pilot burner, a service burner head, an ignition burner head in firing relation to the pilot burner and having a discharge vent in igniting relation to the service burner head, individual mixing tubes leading one to the ignition burner head and one to the service burner head respectively, each of said tubes 25 and its respective burner head defining a chamber separate from the other tube and its respective burner head, separate means for discharging gas into the respective mixing tubes, and means for discharging excess air and gas from one of said chambers into the other.

3. In a gas burning device, a pilot burner, a service burner, an ignition burner in firing relation to the pilot burner and having a discharge vent in igniting relation to the service burner, individual mixing tubes arranged side by side and leading one to the ignition burner and one to the service burner, separate means for discharging gas into the respective mixing tubes, a continuously open by-pass duct communicating 35 the ignition and service burners, said duct being spaced below the level of the discharge vent of the ignition burner.

4. In a gas burning device, a pilot burner, a service burner, an ignition burner in firing relation to the pilot burner and having a discharge vent in firing relation to the service burner, individual mixing tubes leading one to the ignition burner and one to the service burner, separate gas nozzles for discharging gas into the respective mixing tubes, and means operable to accelerate the initial flow of gas through the ignition burner mixing tube to the discharge vent of the ignition burner.

5. In a gas burning device, a pilot burner, a service burner, an ignition burner in firing relation to the pilot burner and having a discharge vent in firing relation to the service burner, individual mixing tubes leading one to the ignition burner and one to the service burner, separate gas nozzles for discharging gas into the respective mixing tubes, and means for accelerating the initial flow of gas through the ignition burner mixing tube to the discharge vent of the ignition burner, said means comprising a by-pass duct 55 directly communicating with the interiors of the ignition burner and the service burner.

6. In a gas burning device, a pilot burner, a service burner, an ignition burner in firing relation to the pilot burner and having a discharge vent in firing relation to the service burner, individual mixing tubes leading to the ignition and service burners respectively, separate means for discharging gas into the respective mixing tubes, and means for accelerating the initial flow of gas 70 through the ignition burner mixing tube to the

said discharge vent of the ignition burner, said means comprising a by-pass duct directly communicating with the interior of the ignition and service burners, the end of said duct in the ignition burner lying out of the path of direct flow 80 of gas passing into the ignition burner.

7. In a gas burning device, a pair of burner heads having discharge vents, individual mixing tubes communicating with the respective burner heads, a valve casing having discharge ducts discharging respectively into said mixing tubes and an inlet duct communicating the interior of the casing with a source of gas, a rotatable plug in said casing having a feed duct communicable with said inlet duct in one rotated position of the plug and having plug discharge ducts extending transversely of the plug and communicating with said feed duct and respectively with the discharge ducts of the casing, said plug discharge ducts being of the same diameter and in substantially the same position longitudinally of the plug, and being positioned relative to each other and to the casing discharge ducts to effect communication of one with a casing discharge duct, both before and during communication of the other 90 and its respective casing discharge duct consequent upon rotation of the plug, whereby gas is introduced to one of said burners prior to and during the introduction of gas to the other.

8. In a gas burning device, a burner, a valve 105 casing having ducts discharging into said burner and communicating with a gas feed conduit respectively, a rotatable plug in said casing adapted to vary the supply of gas discharged to said burner consequent upon rotation of the plug to 110 predetermined positions, a stem carried by said casing and mounted for independent axial and rotary movement and operably connected to said plug for rotating the same, whereby said plug may be rotated to effect a simmering flame on said 115 burner, a stop rigid with said casing, and axially movable means rotatable by said stem and engageable with said stop in one rotated position for stopping rotation of the plug, said means being positioned relative to the plug passages for stopping rotation of the plug in said simmering position when the plug is rotated from open toward a cut-off position, said means and stop being disengageable consequent upon axial movement of the stem whereby the plug may be rotated from 120 the simmering position to cut-off position.

9. In a gas burning device, a burner, a valve 125 casing having ducts discharging into said burner and communicating with a gas feed conduit respectively, a rotatable plug in said casing adapted 130 to vary the supply of gas discharged to said burner consequent upon rotation of the plug to predetermined positions, a stem carried by said casing and mounted for independent axial and rotary movement and operably connected to said plug for rotating the same, whereby said plug may be rotated to effect a simmering flame on said 135 burner, a stop rigid with said casing, and axially movable means rotatable by said stem and engageable with said stop in one rotated position for stopping rotation of the plug, said means being positioned relative to the plug passages for stopping rotation of the plug in said simmering position when the plug is rotated from open 140 toward a cut-off position, said means and stop being disengageable consequent upon axial movement of the stem whereby the plug may be rotated from the simmering position to cut-off position, and means for adjusting the position of 145 150

the stop whereby simmering flames of given intensity may be obtained.

10. In a fuel burning device, a service burner, an ignition burner integral therewith, said burners comprising a hollow body having upwardly discharging exhaust vents and a mixing tube leading into said body, a partition within said body and mixing tube, said partition extending longitudinally of said tube and dividing the in-

terior of the body into separate compartments and dividing said mixing tube into separate channels, one channel communicating with one compartment of the body and one communicating with the other, a by-pass passage in said partition wall near the burner compartments and spaced below the discharge vents thereof.
